UNITED STATES PATENT OFFICE.

JOSEPH W. PHILBROOK, OF WEST ROXBURY, MASSACHUSETTS.

DESIGN FOR GLASS BOTTLES.

Specification forming part of Design No. **6,983**, dated November 4, 1873; application filed October 24, 1873.
[Term of Patent 14 years.]

To all whom it may concern:

Be it known that I, JOSEPH W. PHILBROOK, of West Roxbury, in the county of Norfolk and State of Massachusetts, have invented a Design for Glass Bottles, of which the following is a specification:

The nature of my design is fully represented in the accompanying photographic illustration, to which reference is made.

A glass bottle is made in the shape of a bust of the human figure, and is used as a bottle for the ordinary purposes of such an article. Different varieties of wines and other liquors produce different colors and shades, and give a pleasing effect. Large bottles may be made,

and, having been filled with colored liquid, may be placed before a light to heighten the effect.

a is the base of the bottle, and *b* the nose or outlet, in which the stopple is placed.

Having thus fully described my invention, what I claim is—

The above-described design for a bottle, of the shape substantially as shown in the accompanying illustration.

JOSEPH W. PHILBROOK.
